US0D1088068S

(12) **United States Design Patent** (10) **Patent No.:** **US D1,088,068 S**
(45) **Date of Patent:** **** Aug. 12, 2025**

(54) **3D PRINTER FILAMENT DRYER BOX**

(71) Applicant: **Lifeng Feng**, Cixi (CN)

(72) Inventor: **Lifeng Feng**, Cixi (CN)

(**) Term: **15 Years**

(21) Appl. No.: **29/984,237**

(22) Filed: **Jan. 14, 2025**

(51) **LOC (15) Cl.** **15-09**

(52) **U.S. Cl.**

USPC **D15/122**

(57) **CLAIM**

The ornamental design for a 3D printer filament dryer box, as shown and described.

DESCRIPTION

FIG. 1 is a first perspective view of a 3D printer filament dryer box showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the 3D printer filament dryer box that form no part of the claimed design.

1 Claim, 8 Drawing Sheets
